ABSTRACT OF THE DISCLOSURE

A closable air inlet assembly, often known as a "vault air valve," for ventilating a bank vault or the like is disclosed. The assembly features a horizontally sliding, door-like closure which is suspended in such manner that, even when the assembly is placed in the floor, ceiling or side wall of a vault, the heavy door may be readily slid open or closed by a relatively small electric motor. The door is normally opened and closed from an electrical control panel within the vault, and a solenoid activated latch positively maintains the door in its closed position. An auxiliary electrical control panel is disposed outside the vault but is capable only of closing the door. A hand wheel is included within the vault so that the door may be manually closed, but not opened, in the event of power failure.

This application is a continuation of abandoned application Ser. No. 836,260, filed June 25, 1969.

BACKGROUND OF THE INVENTION

Conventional vault air valves typically employ a slotted, counterbalanced cylinder which rotates about its axis to open and close the air inlet to the vault. Such cylinders are relatively very heavy and costly to manufacture and have been used, rather than relatively lighter and much cheaper sliding doors, because heretofore the latter have not been suspended in a manner such that they may be readily moved by the relatively small electric motors to which such installations, as a practical matter, are limited because of space. The movement of the door must, in view of its weight, be horizontal, no matter in what wall of the vault the assembly is placed. Yet even so, the friction encountered by conventional forms of mounting a door for horizontal, sliding movement has been too great for the limited sized electric motors to surmount. Hence, as mentioned, the practice has necessarily been to use the even heavier and much more costly counterbalanced cylinder. Accordingly, the primary object of the present invention is the provision of a vault air valve which employs a horizontally sliding door suspended in such a manner that it may be moved by a relatively small electric motor, together with appropriate circuitry for controlling operation of the motor and the door.

SUMMARY OF THE INVENTION

Essentially the horizontally sliding door of the present invention travels on a pair of spaced cylindrical ways, horizontally disposed, and is suspended on the latter by means of two pairs of "ball bushings" which permit relatively friction-free linear, rather than rotary, movement of the door relative to the ways. The door is much lighter in weight than a typical cylindrical door having an equivalent air inlet opening and is moved back and forth by a horizontal rack carried by the door which is driven by a relatively small reversible electric motor and gear train. A hand wheel is provided for closing the door in the event of power failure, and a latching mechanism positively locks the door in its closed position until a latch bolt is withdrawn upon activation of a solenoid. Hence the hand wheel alone cannot open the door but only close

2

it. A three position, rocker switch is located on a panel in the vault. In one of its circuit-making positions, that switch activates the motor and the latch solenoid, withdrawing the latch plunger, to open the door, whereupon a second switch closes to activate a signal lamp to indicate the door is open and at the same time sets up the motor reversing circuit for closing the door. When the door opening movement is complete, a third switch opens the circuit to the motor. The other circuit-making position of the rocker switch closes an alternate circuit to the motor through the second switch to reverse the same and close the door, the latter circuit and that to the signal lamp being broken by opening of the second switch upon completion of the door closing. A fourth switch and another signal light are located on a panel outside the vault, the latter switch being wired in parallel with the door closing circuit only of the first switch so that the door may be closed, but not opened, from outside the vault. Finally, a fifth switch, closed by opening movement of the door, activated an alarm system operative during off-hours should an attempt be made to open the air valve during such time.

BRIEF DESCRIPTION OF THE DRAWINGS

FIG. 1 is a horizontal sectional view through a wall of a typical vault illustrating a top plan view of a vault air valve according to the present invention installed therein.

FIG. 2 is a front elevation of the vault air valve of FIG. 1 showing its appearance from within the vault.

FIG. 3 is a vertical sectional view taken along the line 3—3 of FIG. 2.

FIG. 4 is a front elevation of the vault air valve assembly itself, with the inside cover plates removed, showing the door in its fully closed position.

FIG. 5 is similar to FIG. 4 but illustrates the door in its fully open position.

FIG. 6 is a vertical sectional view taken along the line 6—6 of FIG. 4, details of the door latching mechanism being omitted for purposes of clarity.

FIG. 7 is a vertical sectional view taken along the line 7—7 of FIG. 4 illustrating the door latching mechanism.

FIG. 8 is a schematic illustration of the electrical circuit by which opening and closing of the door is controlled.

DESCRIPTION OF THE PREFERRED EMBODIMENT

The air inlet assembly includes an elongated, rectangular housing 10 having a bottom wall 11, top wall 12 and end walls 13 and 14 of suitable steel plate appropriately lap welded to each other. The outer or rear wall 15 overhangs the other four walls and is relatively much thicker, consisting of a laminate formed of a copper plate disposed between two steel plates as is customary in order to frustrate penetration of the rear wall 15 by cutting torches. The housing 10 is divided, somewhat asymmetrically, into a left-hand, with respect to the drawings, machinery compartment 16 and a right-hand air ducting compartment 17 by means of a thick, upright steel partition plate 18 secured to a pair of lower and upper angle brackets 19 fixed in turn to the inner faces of the bottom and top walls 11 and 12, respectively. The portion of wall 15 forming the rear of compartment 17 is rectangularly centrally apertured to provide an air inlet 20. The entire housing 10 is typically disposed horizontally in the wall 21 of a vault and suitable duct work 22 leads therethrough from a source of fresh air to the air inlet 20.

The rear edge of partition plate 18 is spaced forwardly of the inner face of the rear wall 15 in order to accommodate a pair of vertically spaced, horizontally disposed ways 25, in the form of cylindrical bars, whose respective ends are mounted in two pairs of pillow blocks 26

secured to the inner face of rear wall 15 closely adjacent the bottom and top walls 11 and 12, the ways 25 extending nearly the entire width of housing 10. The ways 25, in turn, support a rectangular plate door 27 disposed therebetween, the door 27 being also of laminate construction like rear wall 15, and in close face-to-face relation thereto. The door 27 is fitted for horizontal sliding movement along and between ways 25 by means of two spaced pairs of finger brackets 28 recessed in the forward face of door 27 and extending vertically beyond its upper and lower edges, the outer end of each bracket 28 carrying a linear ball bearing 29 through which passes one of the ways 25. The linear ball bearings 29 permit relatively friction-free passage of the door 27 horizontally back and forth along ways 25 and are manufactured by Thomson Industries, Inc. of Manhasset, N.Y., and sold under the trademark "Ball Bushings." Movement of the door 27 is accomplished by means of a horizontally extending, downward turned rack 30, secured to the inner face of door 27 just above its lower edge, the rack 30 being driven by a pinion gear 31 carried on one end of a transverse shaft 32 journaled between a pair of spaced upright members 33 which are surmounted by a platform plate 34 and submounted by a base plate 35 secured to the bottom wall 11. Intermediate the uprights 33 a bevel gear 36 is fixed to the shaft 32 which engages a similar gear 37 driven by a low torque, reversible electric motor M and gear box of any suitable sort mounted vertically atop the platform plate 34. The other end of shaft 32 is carried out beyond housing 10 and fitted with a suitable handwheel 38. Hence, rotation of motor M or handwheel 38 in either direction will cause the rack 30 and pinion 31 to move door 27 horizontally to and fro to expose or close, as the case may be, the air inlet 20 in the rear wall 15; however, a latching mechanism next to be described is provided to prevent the door 27 from being opened by either motor M or handwheel 38 until the latch is released.

The latching mechanism comprises an angle 40 fitted to the inner face of door 27 adjacent its upper left-hand corner, with respect to FIGS. 4 and 5, the angle 40 having a horizontal latch plate 41 extending forwardly therefrom and beveled as indicated at 42 along its right-hand edge. A solenoid S is mounted to the left-hand face of partition plate 18 with its armature 43 vertically disposed and connected by a suitable linkage 44 to the lower end of a latch bolt 45 slidable in a vertical bore through a steady block 46 mounted by a bracket 47 to the left-hand face of partition plate 18 above the solenoid S and in alignment with its armature 43. The armature 43, linkage 44 and latch bolt 45 are upwardly biased so that as the door 27 closes, the bevel 42 of the latch plate 41 depresses the latch bolt 45 in order that it may engage an aperture 48 in the latch plate 41, as shown in FIGS. 4 and 7. Hence, when in its closed position, the door 27 cannot be opened either by motor M or handwheel 38 until the solenoid S is activated, as hereinafter described. To the top face of latch plate 41 is fixed a switch operating plate 49 having a tang 50 extending forwardly from the inner face of door 27 to beyond latch plate 41 for purposes to be hereinafter described. Finally, the exposed portions of ways 25 in the compartment 17 are enclosed by a pair of removable U-shaped channels 51 of sheet metal, the upper one only being shown in FIGS. 4 and 5, mounted by means of hand screws 52 to a pair of blocks 53 disposed forward of ways 25 on the bottom and top walls 11 and 12. The open side of compartments 16 and 17 is closed by a pair of abutting cover plates 54 and 55, the latter one being apertured at 56 congruent and in alignment with the aperture 20 in the rear wall 15 for passage of air into the vault when the door 27 is open.

The electrical control circuitry for opening and closing the door 27 is disposed partly within the machinery compartment 16 and partly on a pair of control panels CP-1 and CP-2, as indicated in FIG. 8. One side of the motor

M and solenoid S are wired in parallel by leads 60 and 61 into one side of a typical 110 v. AC power source entering CP-1 and connected into compartment 16 through a suitable terminal block T, the panel CP-1 being mounted 5 within the vault adjacent housing 10 while the panel CP-2 is mounted outside the vault adjacent its door. The panels CP-1 and CP-2 also mount a pair of indicator lamps L-1 and L-2 connected in parallel into the other side of the power source by leads 62 and 63. To the lead 10 63 is also connected the terminals A-1 and B-1 of the conjoint switch arms of a three-position, D.P.D.T. rocker switch SW-1 mounted on CP-1. When the switch arms of SW-1 are in mid-position (as shown) no circuit is made through any of the switch contacts A-2, B-2 or B-3, the 15 contact A-3 being unused; the circuit through contacts A-2 and B-2 are momentary while that with contacts A-3 and B-3 is maintained. The lead 63 is also connected to terminal A-1 of the switch arm of a normally open, S.P.S.T. rocker switch SW-2 mounted on panel CP-2, the 20 circuit through whose contact A-2 is maintained, the latter contact being connected by lead 64 to the contact B-3 of SW-1. The contact A-2 of SW-1 is wired in series by lead 65 to the other side of the solenoid S; the contact B-2 of the same switch is wired in series by lead 66 25 through a normally closed, S.P.S.T. microswitch SW-3 mounted on the bottom wall 11 in the compartment 16 so that SW-3 is opened when its switch arm SW-3a is depressed by the lower edge of the door 27 while the latter is in its fully open position (see FIG. 5); and the contact B-3 of SW-1 is wired in series by lead 67 to the 30 terminal B-1 of the conjoint switch arm of a normally closed, D.P.S.T. microswitch SW-4 vertically mounted on the bracket 47 forward of the steady block 46 such that the tang 50 engages the switch arm SW-4a of SW-4 to hold the latter open when the door 27 is in its closed position SW-3 and the switch contact B-2 of SW-4 are 35 wired in parallel by leads 68 and 69, between which is a capacitor C mounted on the bottom wall 11 in the compartment 16, into the forward and reverse windings of the motor M for respectively opening and closing the door 27. The switch arm terminal A-1 of SW-4 is wired in series by leads 70 and 71 to the other sides of lamps L-1 and L-2 while the switch contact A-2 of SW-4 is connected by lead 72 to the lead 60. Finally, a normally 40 closed, S.P.S.T. microswitch SW-5 is mounted on the under face of the top wall 12 so that it is held closed by engagement of its switch arm SW-5a and the upper face of the switch operating plate 49 when the door 27 is in its closed position. SW-5 is wired in series as indicated with an alarm circuit (not shown) so that any unauthorized opening of door 27 during off-hours will activate the alarm when the operating plate 49 disengages from the switch arm SW-5a as the door 27 is moved. Of course, during normal banking hours, the alarm circuit is otherwise deactivated. With the alarm circuit deactivated, therefore, operation of the vault air valve is as follows, FIG. 8 showing the positions of the various switches when the door 27 is in its closed position:

To open door 27, SW-1 is depressed and held to engage its contacts A-2 and B-2, thus completing the circuit to motor M and solenoid S through leads 62, 63, 65 and 66, whence the latch bolt 45 is withdrawn from the latch plate 41 and the forward windings of the motor M are activated through SW-3 and lead 68 to cause the door 27 to open in the manner heretofore explained. The accompanying movement of tang 50 as door 27 opens causes SW-4 to close, one side of which completes the circuit to indicator lamps L-1 and L-2 through leads 60, 72, 70 and 71, while the other side of SW-4 sets up the circuit to the reverse windings of motor M through leads 67 and 69. As long as SW-1 is held depressed, the door 27 continues to open until its lower edge contacts the switch arm SW-3a of SW-3, opening the latter and thus the circuit through lead 66, SW-4 and lead 68 to the forward windings 75 of the motor M. SW-1 is then released, the two

lamps L-1 and L-2 remaining lighted to indicate the door 27 is open. To close the latter, SW-1 is simply depressed to engage the contact B-3, whereby the circuit to the reverse windings of the motor M is closed through leads 62, 63 and 67, SW-4 and lead 69, the latter portion of this circuit, it will be remembered, having been set up by the closing of SW-4 upon disengagement of the tang 50 and the switch arm SW-4a when door 27 opened. Hence door 27 moves towards its closed position, whence SW-3 is reclosed by release of its switch arm SW-3a by door 27 to set up the circuit previously described to the forward windings of motor M, until the tang 50 again engages switch arm SW-4a, thus opening SW-4 and the circuits to the motor M and the lamps L-1 and L-2, the latter indicating that the door has in fact closed. At the same instant, the latch bolt 45 having first been depressed by the bevelled edge 42, snaps upward into its aperture 48 in latch plate 41 securing the door 27. If for some reason the vault should inadvertently be locked up with the door 27 left open, the switch SW-2 on the panel CP-2 outside the vault can be closed, which, it will be observed, accomplishes the same thing as the door closing circuit of SW-1 since the latter is in parallel with SW-2. As an alternative, SW-1 can simply be incorporated in the vault door itself so that as the latter is opened or closed SW-1 is also activated to open or close the door 27. In the event of a power failure, the door 27 may, as described above, be closed but not opened from within the vault by means of the handwheel 38.

While the invention has been described in terms of a particular embodiment, being the best mode presently known of carrying out the invention, and detailed descriptive language has been used, the invention is not in fact so limited. Instead, the following claims are to be read as encompassing all modifications and adaptations of the invention falling within the spirit and scope thereof.

I claim:

1. In a vault air valve assembly for mounting in the outer wall of a bank vault or the like for supply of fresh air thereto, said assembly including a housing having a rear wall with an air inlet therein, the improvements in combination therewith comprising: a generally plate-like door disposed in said housing in face-to-face relation with said rear wall and selectively horizontally movable to an open position and to a closed position to respectively open and close said air inlet by sliding movement thereacross; friction reducing means mounting said door for said sliding movement, said means comprising horizontally disposed cylindrical ways in said housing and a plurality of cylindrical linear ball bearings secured to said door and encompassing said ways, said bearings permitting relatively friction-free linear movement of said door along said ways; latch means operative in said door closed position to maintain said door closed; and means for controlling movement of said door along said ways, said means comprising an electric motor of the reversible, low torque type having forward and reverse windings, an electrical solenoid for selectively releasing said latch means in order to permit opening of said door, and an electrical control circuit therefor, said circuit including a normally open first switch having a first circuit making member with first and second circuit making positions and a second circuit making member conjointly operated with said first circuit making member, said second circuit making member being

open when said first circuit member is open and in circuit making position in series with said solenoid when said first circuit making member is in its first circuit making position, a normally closed second switch in series with the first position of the circuit making member of said first switch and the forward windings of said motor, a normally closed third switch in series with the second position of the circuit making member of said first switch and the reverse windings of said motor, said second and third switches being operatively associated with said door so that said second switch is open when said door is in its fully open position and closed when said door is other than in its fully closed position and said third switch is open when said door is in its fully closed position and closed when said door is in other than its fully open position, the circuit making member of said first switch in the first of its circuit making positions energizing the forward windings of said motor through said second switch to open said door and in its second circuit making position energizing the reverse windings of said motor through said third switch to close said door, a normally open fourth switch in parallel with the second circuit making position of the first circuit making member of said first switch, said first switch being disposed for operation from within the vault and said fourth switch being disposed for operation from outside the vault.

2. The assembly of claim 1 including a pair of indicator means in parallel with each other, one of said means being disposed for operation within the vault and the other being disposed for operation outside the vault; and a normally open fifth switch in series with said indicator means, said fifth switch being operatively associated with said door to be closed to energize said indicator means when said door is in other than its fully closed position.

3. The assembly of claim 1 wherein said door moving means includes a gearbox operatively associated with said door and motor, said gearbox being capable of driving said motor when deactivated by said control circuit upon manually impelled opening movement of said door as well as being driven by said motor when activated by said control circuit, a horizontal rack fixed to said door, a pinion gear engaging said rack and driven by said motor.

4. The assembly of claim 3 including manual means disposed for operation from within the vault for manually rotating said pinion gear effective to move said door from its open to its closed position.
